(57) **CLAIM**

The ornamental design for a safety harness, as shown and described.

DESCRIPTION

FIG. 1 is a front elevational view of our safety harness shown on a phantom torso;

FIG. 2 is a rear elevational view thereof shown on a phantom torso;

FIG. 3 is a front flat view thereof; and,

FIG. 4 is a rear flat view thereof.

The broken lines showing a torso in FIGS. 1 and 2 illustrate environmental structure only and do not form part of the claimed design. The broken lines shown on the safety harness represent stitching that does form part of the claimed design.
